UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed July 13, 1922. Serial No. 574,762.

To all whom it may concern:

Be it known that I, GEORGE M. LITTLE, a citizen of the United States, and a resident of Pittsburgh, in the county of Allegheny and State of Pennsylvania, have invented a new and useful Improvement in Lightning Arresters, of which the following is a specification.

This invention relates to resistor materials, more particularly to plates of high-resistance material adapted for use in lightning arresters of the disk-pile type.

In the copending application of J. Slepian for lightning arresters, filed February 11, 1922, Serial No. 535,810 and assigned to the W. E. & M. Co., is described a new type of lightning arrester comprising a series of plates or disks of high-resistance material placed in contact with each other. Suitable terminals secured to the end plates of the structure are utilized to connect the same in a suitable electrical circuit to be protected.

Owing to the high resistance of the material, substantially no current passes therethrough at the normal operating voltage of the circuit to be protected, but, upon the application thereto of a high abnormal voltage, such as a lightning discharge, the gaps between adjacent contacting plates break down, initiating a glow discharge which spreads uniformly over the surfaces of the plates, thus providing a discharge path for the abnormal voltage. The outstanding characteristic of the glow-discharge arrester of the above-mentioned application is that the discharge is interrupted when the voltage falls to a value but slightly below the breakdown voltage.

It has been found that, in some cases, the power current tends to flow through the lightning arrester after the abnormal voltage has been discharged. This, in a measure, occurs because of fine particles of material which tend to bridge the small gaps between the plates and to the resistance of the plates which must not be so high as to unduly limit the discharge capacity of the lightning arrester.

To obviate this disadvantage, the plates have been provided with integral ribs of high-resistance material in order that the plates may make contact at a relatively small number of points of high resistance and, therefore, prevent the power current

from flowing after the lightning discharge has passed through the arrester. Generally, the ribs have been made of higher resistance material than the body, this being accomplished by oxidizing them by contact with a heated plate. This improvement is described and claimed in the copending application of J. Slepian for disk structure, filed February 16, 1922, Serial No. 536,910 and assigned to the W. E. & M. Co.

It has been found desirable, in this type of lightning arrester, to have the plates of high-resistance material of large size in order that the discharge capacity of the lightning arrester may be increased. It is, therefore, an object of the present invention to provide a plate structure which shall be adapted to manufacture in large sizes and which shall be simple in construction and efficient in operation.

In practising my invention, I provide a comparatively large plate or disk having a plurality of ribs thereon, the distance between adjacent ribs being small, as compared with the largest dimension of the plate or disk. By the provision of such a structure, I obtain a plate having a comparatively large number of points along which discharge may begin and thereby cause the same to spread rapidly and uniformly over the entire surface thereof. The efficiency of the lightning arrester is thereby increased and the discharge of abnormal voltage is thereby accelerated.

In the accompanying drawings constituting a part hereof and in which like reference characters indicate like parts,

Fig. 1 is a plan view of a plate made, in accordance with my invention;

Fig. 2 is a cross-sectional view thereof taken along the line II—II of Fig. 1, showing a stack of such plates;

Figs. 3 and 4 are plan views of slightly modified forms of my invention;

Figs. 5 and 6 are plan and cross-sectional views, respectively, of a still further modification thereof, and

Figs. 7 and 8 are similar views of a somewhat different form thereof.

The disk or plate 1, which may be made of kaolin, carborundum and graphite is provided with parallel ribs 2 having intermediate portions 3 therebetween, said portions being small relative to the diameter of the

disk. Preferably the ribs 2 are of higher-resistance material than the body portion and may be obtained by placing the surface of the plate in contact with a heated surface which oxidizes the rib portions, removing a portion of the carbon therefrom and increasing the resistance thereof to any desired degree.

In Fig. 3 I have shown a similar structure comprising two sets of ribs 4 and 5, the ribs of each set being parallel to each other and the sets being arranged at right angles. Spaces 6 constitute the depressed portions between adjacent and intersecting ribs. In Fig. 4 I have shown a disk structure having concentric ribs 7 and intermediate depressed portions 8 therebetween.

In the embodiments shown in Figs. 3 and 4, it may be difficult to satisfactorily burn out the carbon uniformly over the entire surface of the plate because of the inability of oxygen from the air to penetrate to the interior during the heating operation. I, therefore, provide a structure, as shown in Figs. 5 and 6, in which the disk 1 is provided with concentric ribs 9 having intermediate portions 10 therebetween. An opening 11 is provided centrally of the disk in order that, when said disk is placed upon a hot surface in order to oxidize the ribs, oxygen may have access thereto, both from the outside of the disk 1 and through the opening 11 therein.

Another structure which has the desirable characteristics of those described above consists of a rectangular plate 1 (Figs. 7 and 8), the length thereof being considerably greater than the width, which is provided with ribs 12 and 13 along the sides thereof, leaving the central portion 14 depressed. By reason of the proximity of ribs 12 to each other, as compared with the length of the plate, a discharge, starting adjacent to the ribs, will spread in all directions and thereby rapidly and uniformly cover the entire surface of the plate.

Although I have shown and described several embodiments of my invention, it is apparent that my invention is not limited to the specific details set forth. For instance, instead of a circular or rectangular plate, I may provide a plate of any desired shape and the ribs thereon may be formed in any suitable manner. In all the modifications shown herein, the ribs are uniformly spaced in regular patterns but I am not limited to such spacing since irregular spacing of the ribs will give substantially the result above set forth. These and other changes may be made in the details of construction of my plate, my invention being limited only by the claims appended hereto.

I claim as my invention:

1. A plate of high-resistance material comprising a substantially flat body portion and material of at least one of said plates having

a plurality of ribs thereon, the distance between adjacent ribs being substantially less than the largest dimension of said plate, the resistance of said ribs being higher than that of the body portion.

2. An excess-voltage protective device comprising at least one pair of juxtaposed plates, and a plurality of high-resistance spacing means interposed between said plates, the distance between said spacing means being substantially less than the largest dimension of said plates, and the resistivity and spacing being such that the protective device permits a relatively large current-flow at voltages above a predetermined value and prevents any substantial current-flow at voltages below said value.

3. An excess-voltage protective device comprising at least one pair of juxtaposed high-resistance plates having a discharge gap therebetween, and a plurality of high-resistance spacing means interposed between said plates, the distance between said spacing means being substantially less than the largest dimension of said plates.

4. A protective device comprising at least one pair of juxtaposed high-resistance plates, and a plurality of high-resistance spacing means interposed between said plates, the distance between said spacing means being substantially less than the largest dimension of said plates, the specific resistance of said spacing means being higher than the specific resistance of said plates.

5. An excess-voltage protective device comprising at least one pair of juxtaposed high-resistance plates having a discharge gap therebetween, at least one of said plates having a plurality of integral ribs contacting with the other plate, the distance between said spacing ribs being substantially less than the largest dimension of said plates.

6. An excess-voltage protective device comprising at least one pair of juxtaposed high-resistance plates having a discharge gap therebetween, at least one of said plates having a plurality of integral ribs of increased specific resistance contacting with the other plate, the distance between said spacing ribs being substantially less than the largest dimension of said plates.

7. A space-current discharge device comprising at least one pair of electrode plates having a discharge gap therebetween, one of said plates carrying a plurality of ribs contacting with the other plate for spacing the same, the distance between said spacing ribs being substantially less than the largest dimension of said plates.

8. A space-current discharge device comprising at least one pair of electrode plates having a discharge gap therebetween, the material of at least one of said plates having

such resistivity as to cause the discharges to spread out, said plate carrying a plurality of ribs contacting with the other plate for spacing the same, the distance between said 5 spacing ribs being substantially less than the largest dimension of said plates.

9. An excess-voltage protective device comprising at least one pair of juxtaposed plates, and a plurality of high-resistance 10 spacing means interposed between said plates, the distance between said spacing means being substantially less than the largest dimension of said plates, and the 15 spacing being such that the space-current flow between the plates always takes the form of a glow discharge.

10. An excess-voltage protective device comprising at least one pair of juxtaposed high-resistance plates, and a plurality of 20 high-resistance spacing means interposed between said plates, the distance between said spacing means being substantially less than the largest dimension of said plates,

and the resistivity and spacing being such that the protective device permits a relatively large current-flow at voltages above a predetermined value and prevents any substantial current-flow at voltages below said 25 value.

11. A space-current discharge device comprising at least one pair of electrode plates having a discharge gap therebetween, one of said plates carrying a plurality of ribs contacting with the other plate for spacing the same, the distance between said spacing ribs 30 being substantially less than the largest dimension of said plates, the organization being such as to cause a glow discharge at voltages above a predetermined value and to permit no space-current discharge at voltages 35 materially below said value.

In testimony whereof, I have hereunto subscribed my name this 11th day of July 1922.

GEORGE M. LITTLE.
